UNITED STATES PATENT OFFICE

2,382,354

WALL CABINET

Nathaniel B. Wales, New York, N. Y., assignor to
 Norman Bel Geddes, doing business as Norman
 Bel Geddes, and Company, New York, N. Y.

Application October 31, 1944, Serial No. 561,259

6 Claims.

(Cl. 312—151) *Patents May be filed in this office for the use of the public in elevators, lifts, and the like, one of the two rolling supports showing a fragment of the shelf element.*

Figure 5 is a front view shown with the right hand portion in section on line C—C in Figure 2, with the shelf element in its upper position, taken on line D—D in Figure 2.

Figure 6 is a plan view in enlarged section, taken on line B—B in Figure 5, showing in detail the one upper rolling contact suspension point of the shelf element as guided by the cylinder of the hydraulic system.

Referring to the several drawings similar numerals refer to similar parts.

In Figure 1, numeral 1 is the wall cabinet, 2 is the shelf element consisting of a structure having an open front and shelves 13 which may be composed of a plurality of superposed shelves together with rear and side walls as a unit element, 3 is the front panel in cabinet 1, hinged along its upper end by hinge 10, see Figure 2, which is attached to strip 11, forming a top section of the cabinet casing 1, and which in turn is secured to hinge 12, which is likewise secured to the permanent portion of the top of cabinet 1. In this manner the front panel 3 will easily rise and move outward if any obstruction on shelf 13 protrudes, as and when shelf 13 is elevated above the lower edge of front panel 3.

A protective casing 14 also surrounds the shelf space which the hydraulic cylinder 4 occupies when the shelf element rises into cabinet 1. A piston 15, of any suitable construction, fits within cylinder 4, and has a piston rod 7, which passes through a packing gland 16 in the lower end of cylinder 4. The piston rod 7 is conventionally secured to the shelf element 2 through a plate 8 fastened to the lower portion of the shelf element.

A cylinder head 6 is secured to the top of cylinder 4. A bleeder pipe 17, entering the top of cylinder 4, passes down behind the shelf element 2 and in front of the rear panel of the cabinet 1 and enters the drain pipe connection 18, thereby permitting water leakage from piston 15 and trapped air to be properly vented into the drain.

45 A control valve 9, with the rotatable element 19, having therein port 20 is arranged to register the cylinder connecting pipe 21 alternately with drain pipe 18 to lower the shelf element 2, or with water main pipe 22 when it is desired to raise shelf element into cabinet 1. A handle 23 and connecting shaft 24 are shown as a means to operate valve 9.

It is to be noted that the cylinder 4, see Figure 2, is shown at the rear of the shelf element 2 in order to minimize its interference with the useful

This invention relates to a wall cabinet and especially in reference to its elevator mechanism incorporated with the shelf element, and as one embodiment of this invention, I show it in the form of a kitchen cabinet.

One of the objects of this invention is to permit a series of shelves to be lowered at will by simply pressing a button, or its equivalent, so that the contents will be easily accessible. By doing this the shelves may be located much higher on the wall than is now common practice, and in this manner space now unused for shelf area can be accessibly utilized for storage space.

Another object is to attain absolute safety by providing a yielding cabinet panel, so that if the operator's hand should be caught between a shelf and the front panel of the cabinet, the hand can be withdrawn without injury, even though the hydraulic elevating power, or the like, is still in operation.

Another object is to obtain noiseless operation of the lowering and raising mechanism, which mechanism must be of the simplest character.

A further object is to sustain the overhung and possible unbalanced weight of the articles on the shelves, when the shelf element is in a lowered position, by unseen mechanism consisting of the fewest possible components.

These overhung and unbalanced weight components are properly sustained by a three point suspension, two of which points of support are obtained directly from the wall against which the shelf element is in rolling contact during its "up and down" movement. In this manner no guiding mechanism is visible and yet the shelf element is always in alignment with the cabinet, so that the actuating mechanism and in particular the sealing gland in the cylinder base will not leak during normal use.

Further objects and details will be more specifically described and illustrated in the following specifications and drawings in which:

Figure 1 is an isometric exterior elevation showing the shelf element in its lowered position below the stationary wall cabinet.

Figure 2 is an end elevation of the wall cabinet, shown partially in section, with the shelf element at its extreme lowered position. The rolling shelf supports against the wall, or its equivalent, are clearly indicated.

Figure 3 is an enlarged section through the control valve of the hydraulic elevating system taken on line A—A in Figure 2.

Figure 4 is an enlarged end view in elevation of

space of the shelf area. This position of the lifting force, which elevates and sustains the shelf element, produces an "off center" gravity component of the weight imposed on the shelf element. For this reason and in order to achieve the simplest form of suspension, which will also be invisible, I utilize a three point suspension system which is clearly shown in Figure 5 and Figure 6. The dotted lines 35 and 36 are drawn in Figure 5 to show this relationship.

A cross-head member 25 partially surrounds the cylinder 4, a portion being omitted to permit the cross-head to pass by the cylinder support arms 26 and member 21, which are suitably secured to the back panel 21 of the cabinet 1. Rollers 28 are journaled in cross-head 25, and are in rolling contact with the exterior of cylinder 4. The cross-head 25 is suitably secured to the top of the upper shelf 29 of shelf element 2.

This rolling contact cross-head is the upper member of the three point suspension, while the two rollers 30 and 31, secured to the back panel 33 of shelf element 2 complete the three point suspension. The rollers 30 and 31 may be rubber faced wheels in direct contact with the kitchen wall 5, or its equivalent, and referring to Figure 2, directly support the overhung weight of the shelf load, relieving the stuffing-box gland 16 of damaging side thrust.

The operation of the wall cabinet is as follows: Assuming the shelf element is in the position as shown in Figure 5, the handle 23, or its equivalent, is manipulated to turn control valve 9 to the position shown in Figure 3, thus allowing the water filled cylinder 4, which has maintained piston 15 at its uppermost position, to empty, through port 20 in valve 9, into the drain connection 18. The shelf element 2 now falls to the position shown in Figure 2, the rollers 30 and 31, turning as they contact wall 5, support the shelf element during its movement.

When it is desired to restore the shelf element to its position shown in Figure 5, the valve 9 is turned to permit port 20 to register with pipes 22 and 21 and the pressure of the city water service, through water supply pipe 22, forces piston 15 to rise in cylinder 4, thereby elevating the shelf element by virtue of piston rod 7 and its connection through plate 8 with the shelf element 2.

By tests, it has been found that if the roller support wheels 31 are of sufficient width, and made of white rubber, no markings ensue after continued operations on a conventional plaster wall.

What I desire to claim by United States Letters Patent is encompassed in the following claims.

1. A cabinet, adapted to cooperate with a supporting wall, containing a movable shelf element, two laterally spaced rollers secured to the back of said shelf element, actuating means to lower and elevate said shelf element from and into said cabinet, said actuating means including a vertical guide element means on the shelf element engaging said vertical guide element, said vertical guide element and two rollers serving as a three

point suspension to guide said shelf element in its travel from and into said cabinet.

2. A cabinet, adapted to cooperate with a supporting wall, containing a movable shelf element, two laterally spaced rollers secured to the back of said shelf element, actuating means to lower and elevate said shelf element from and into said cabinet, said actuating means including a vertical guide element, a three point suspension to guide said shelf element in its travel, utilizing as one upper central guiding support, in said suspension, said vertical guide element and said rollers contacting said supporting wall as the other two points in said suspension.

3. A cabinet, adapted to cooperate with a supporting wall, containing a movable shelf element, and comprising a hydraulic motor, including a vertical cylinder to lower and elevate said shelf element from and into said cabinet, a three point suspension to guide said element in its travel, utilizing as one upper central guiding support, said vertical cylinder secured to said cabinet and two roller guiding supports secured to the rear of said shelf element and contacting said supporting wall.

4. A cabinet, adapted to cooperate with a supporting wall, containing a movable shelf element having a slide element and two laterally spaced rollers secured to the rear thereof, and comprising motive means to lower and elevate said shelf element from and into said cabinet, said motive means including a vertical guide secured to and positioned within, and at the rear of said cabinet and engaged by said slide element secured to said shelf element, a three point suspension serving as a guide for said shelf element in its travel, composed of said vertical guide and said two rollers secured to the rear of said shelf element and contacting said supporting wall.

5. A cabinet, comprising a main body, a front panel and an open lower end, a shelf element slideably mounted in the cabinet and adapted to be elevated or lowered into and out of said cabinet, power means to raise and lower said shelf element and manual control means therefor, accessible from the front of said cabinet and hinged means attaching the top of the front panel of said cabinet to the main body thereof, to permit said panel to freely move both upward and outward from said cabinet in case an obstruction elevated by said power driven shelf encounters the lower edge of said front panel.

6. A cabinet, adapted to cooperate with a supporting wall, containing a movable shelf element, and comprising hydraulic cylinder actuating means, secured to said cabinet, to lower and elevate said shelf element from and into said cabinet, crosshead means attached to said shelf element and engaging said cylinder to align said shelf element with said cabinet, roller supports, secured to the rear of said shelf element and engaging said wall, to support the overhung weight on said shelf element when said shelf element is lowered from said cabinet, and a manual control for said hydraulic actuating means.

NATHANIEL B. WALES.
